UNITED STATES PATENT OFFICE.

WILLIAM M. TULLEY, OF MARION, INDIANA.

DIPPING-MACHINE.

No. 872,863.

Specification of Letters Patent.

Patented Dec. 3, 1907.

Application filed April 29, 1907. Serial No. 370,932.

To all whom it may concern:

Be it known that I, WILLIAM M. TULLEY, a citizen of the United States, residing at Marion, in the county of Grant and 5 State of Indiana, have invented certain new and useful Improvements in Dipping-Machines; and I do declare the following to be a full, clear, and exact description of the invention, such as will enable others skilled 10 in the art to which it appertains to make and use the same.

This invention relates to dipping machines, which may be employed to dip articles, such as machine elements, castings, articles of 15 furniture and the like in a bath of paint and then discharge the painted articles, thereby dispensing with the manual application of the paint; and which may be also employed in dipping slaughtered hogs in a 20 vat of hot water preparatory to dressing them.

The object of the invention is to provide an improved machine of this kind, which is practically automatic in action, that is to 25 say, aside from the presence of an attendant to supply the work or articles to be dipped to the machine to cause the latter to perform the functions of moving the work to the vat or receptacle, dipping such articles or work 30 in such receptacle, elevating and discharging the work or dipped articles with rapidity and accuracy and without necessitating an attendant to start and stop the machine at frequent intervals, or at different stages 35 in the procedure, whereby a larger output of finished work may be secured in a given time.

With the above and other objects in view, as will appear as the nature of the 40 invention is better understood, the same consists in the novel construction and combination of parts of a dipping machine, as will be hereinafter fully described and claimed.

45 In the accompanying drawings, forming a part of this specification, and in which like characters of reference indicate corresponding parts,—Figure 1 is a view in front elevation, partly in section, of a portion of the machine constituting the present invention; Fig. 2 is a similar view with the parts shown in extended position; Fig. 3 is a view in end elevation, partly in section, looking from the left hand side of Fig. 1; 50 Fig. 4 is an end elevation looking from the left hand side of Fig. 1, and showing the

operation of the elevators and of the mechanism connected therewith; Fig. 5 is a detail perspective view of the shifting rod and lever; Fig. 6 is a detail perspective view of the cleats; Fig. 7 is a detail side elevation of the mechanism for raising and lowering the elevators; Fig. 8 is a detail top plan view of the same; and Fig. 9 is a detail sectional view of the same. 60 65

The framework of the machine comprises two channeled guides or standards 1 and 2, which have their lower ends bolted to a suitable base or flooring, and their upper ends connected and braced by a pair 70 of cross-beams 3, as clearly shown in Fig. 1.

Arranged between the standards is a reciprocal skeleton frame that supports the bulk of the operating mechanisms of the apparatus. This frame comprises a straight up- 75 per beam 4 and a drop frame beam 5, the two beams being connected and rendered rigid by brace plates 6, 7, 8 and 8^a. To avoid confusion in the drawings, but four of these brace plates are herein shown; but it is to be 80 understood that any number may be employed that will be found necessary or expedient. Each of the beams 4 and 5 carries at its terminals, rollers 9 that are designed to engage guideways 10 arranged in the op- 85 posed faces of the standards 1 and 2, whereby the frame will be guided vertically in operation and be caused to travel in a determined path. The drop frame is made in the form shown in Fig. 1 to render it more rigid 90 in character, and also to adapt it to support and coact with certain mechanisms herein- after described.

Firmly bolted at its upper portion to the cross beam 3, and at a point intermediate of the ends of the latter, is a guide frame that comprises two beams or members 11, the lower ends of which are stayed and rendered rigid by brace bars 12 and 13 bolted or riveted at their lower ends to the frame member 100 11 and at their upper ends similarly secured to the beam 3. The opposed faces of the beams 11 are provided with guideways 14 that are engaged by a head 15 constituting a portion of one of the elevators that is de- 105 scribed further on.

The apparatus embodies two elevators, one of which, hereinafter termed the dipping elevator, receives the work, lowers it into the dipping tank, and returns it to a point to be 110 discharged from the apparatus, and the other of which elevators, which is hereinafter

termed the discharge elevator, elevates the finished work to an off-take track. The dipping elevator comprises a hollow or box track 16, which is rigidly bolted to and supported by the bend 21 of the beam 5, as clearly shown in Fig. 1. The ends of the track are oppositely beveled, as shown at 17 and 18 in Fig. 3, and are designed to engage with the similarly beveled end of the box track 19 of the discharge elevator and with the like end of the on-take track 20. Said on-take track is fixed, and is here shown as slightly inclined and as supported by hangers 20^a.

15 While it will generally be preferred to employ the form of track shown, it is to be understood that other constructions may be adopted, be it found necessary or desirable.

As will be obvious, it will be necessary that 20 means be provided whereby all of the track sections shall be held in accurate alinement to insure the travel of the trolleys carrying the stock from the on-take track 20 to the track 16, and thence to the track 19 by 25 which the latter is elevated to and discharged onto the fixed off-take track 22, as will presently appear. This track alining means consists of two inverted V-shaped cleats 23 and 24, Fig. 6, that are firmly bolted to the 30 upper sides of the track sections 16, 19, 20 and 22 at the central line of their meeting ends, and project beyond or slightly overlap the same. As will be seen by reference to 35 Figs. 3 and 4, the cleat 23 is the larger of the pair and is designed to receive the projecting end of the cleat 24, and thereby hold the track in alinement. Owing to the coaction between the inclined sides of the cleats, the tracks will be positively forced into alinement when the sections are in operative 40 position. The trolley referred to above, and which is an example of one of the many forms that may be employed, consists in this instance of four wheels 25 carried by two 45 axles that are rigidly bolted to a pair of frame bars 26, and depending from the latter and rigid therewith is a two armed hanger 27, having hooked terminals 28 to engage and support the article to be dipped. Of 50 these trolleys any desired number may be employed, it being designed that there shall be a continuous intermittently moving line passing from the on-take track to the dipping elevator.

55 As will be noted by reference to Fig. 3, the track sections 16 and 19, when in alinement, are in a horizontal position, while the section 20 is inclined in order to cause the travel of the trolleys along the track to be automatic.

60 To prevent interference between two trolleys, and to guard against a trolley running off of the track 20 of a trolley when the dipping elevator is lowered, novel means is provided, and also for shifting a loaded trolley 65 from the track section 20 to the section 16,

and further novel means is provided for holding the trolley in proper position on the dipping elevator and shifting the trolley when the elevator resumes its normal or raised position from the track section 16 to the section 19.

The mechanism for holding a loaded trolley from passing to the track section 16 when the latter is lowered, comprises, in part, an L-shaped lever, that is pivoted at 29 to an 75 arm or bracket 30 secured to the cross beam 3. The upper or short arm 31 of the lever, which occupies a substantially horizontal plane, carries an adjustable weight 32, and the long arm 33 of the lever carries at its 80 lower end a cam or shoe 34 which is connected with the arm 33 by an angular extension 35. The normal position of the cam 34 is such that it will lie in the path of the hanger of a trolley on the track section 20, 85 and thus hold it against movement. In order to shift the cam out of the path of the trolley, there is provided a shaft 36 that is journaled in the lower depending ends 37 of a pair of bars 38, the upper ends of which are 90 firmly bolted to the beam 4 of the vertically-movable skeleton frame, and their lower portions to the beam 5 thereof adjacent to the bend 21. Thence the bars are bent outward and occupy a horizontal position, as shown 95 at 39 in Figs. 3, 4 and 5, and thence bent downward at right angles to the portions 39 to present the bearings 37. This shaft is adapted for rotary and longitudinally reciprocatory motions, the first motion operating 100 through actuation of certain mechanism to shift the cam 34 out of the path of the hanger, and the second motion to shift the trolley from the track section 20 on to the section 16. The first motion, that of shifting the cam 34, is accomplished by a finger 105 40 that is carried by the intermediate portion of an arm 41 that is provided with two spaced collars 42, carrying set screws by which it is rigidly clamped upon the shaft. In addition to the finger 40, the arm carries adjacent to its outer extremity a similar finger 43, the function of which will appear further on. The rotary motion is imparted to the shaft 36 for the purpose of causing the finger 40 to 110 shift the cam 34 by a series of levers 44, 45 and 46. The lever 44 is provided with a collar 47 splined to the shaft 36, and the shaft is provided with a key way 48 that is engaged by a feather key 49 in the collar 47 115 where by it will be seen that the lever 44 will be free to slide longitudinally along the shaft 36, but will be held against turning thereon. The outer end of the lever 44 is provided with a longitudinal slot 50 that is engaged 120 by a pin or bolt 51 carried by the lever 45, which latter is fulcrumed or pivoted intermediate of its ends at 52 to the beam 5. The upper end of the lever 45 is pivotally connected at 53 to the rear end of the lever 46, 125 130

the forward end of which carries a bolt 54 upon which is mounted a roller that works in a slotted track 55 that is secured to the standard 2, the upper portion 56 of which is disposed obliquely to the standard 2, while the remaining portion is arranged parallel therewith and extends to the bottom thereof. This track consists of two bars of metal that are held properly spaced apart by 10 clamps 57 and 58, suitably spaced apart, the latter clamps being bolted to the standard 2. In order to cause the roller of the lever 46 to travel in the track slot 59, the brace plate 8 is provided with two spaced bolts or pins 15 60, between which the upper end of the lever 46 projects, as clearly shown in Figs. 1 and 2. To reduce the friction between the pins and the lever to a minimum, the latter is preferably provided with rollers, as shown.

20 Now, it will be seen that when the reciprocating frame descends, the roller of the lever 46 will be compelled to travel down the inclined portion of the track slot, and this will exert an outward pull upon the lever 46, 25 thereby rocking or drawing the upper end of the lever 45 to the right and projecting its lower end to the left, whereupon the bolt 51, by riding in the slot 50, will force the lever 44 upward and thereby impart a rotary motion 30 to the shaft 36, which will cause the finger 40 to assume an angular position, and out of contact with the cam 34, which cam will now bridge the space through which the trolley moves, and thus hold a loaded trolley 35 against escaping or running off the track 20, as shown in Fig. 2. Upon the return movement of the dipping elevator, as soon as the roller on the lever 46 enters the inclined portion of the track slot, the levers 40 46, 45 and 44 will be actuated in a reverse direction to that above described, causing the finger 40 to assume a horizontal position, and in so doing, by contacting with the cam 34, force it to one side and out of the path of 45 travel of the trolley. The arm 33 is guided for movements to and from the track section 20 by guide arms 61 carried by the track section 20, as clearly shown in Figs. 1 and 2. The finger 43 on the arm 41 is now in the 50 rear of the hanger, and operates to transfer the trolley from the track section 20 to the section 16. This shifting movement of the finger 43 is secured by imparting longitudinal movement to the shaft 36, and this is accomplished by the employment of a lever 55 62, which, as shown in Figs. 1, 2 and 3, is curved, and extends at its lower end through an arm 63, that is loose on the shaft, being provided with a collar for this purpose. The 60 upper end of the lever 62 is secured to a shaft 64, supported in a hanger 65 depending from the beam 4 and in a bearing 66 carried by the brace plate 8^a. The outer end of the shaft has secured to it an arm 67, carrying a 65 roller 68, that is designed to travel on a

spring 69 secured to a fixed hanger 70, bolted to the under side of the fixed beam 3. As shown in Fig. 3 the spring is provided with a shoulder 71 which is provided for the purpose of permitting the roller to pass from the rear side of the spring to the front side thereof, as on the downward movement of the skeleton frame, the roller will travel on the outside of the spring, and on the upward movement of the frame upon the inside thereof. The shifting of the roller to the outside of the spring is secured by a weight 72 carried by an arm 73, rigid with and forming a continuation of the arm 67, as shown in Fig. 3. It will be noted that both of the weights 32 and 72 are movable on their supporting arms, thereby to permit any adjustments that may be necessary to secure the desired result. Now, it will be seen that so long as the roller 68 travels on the inner side of the spring 69, that the shaft 36 will occupy the position shown in Fig. 3, but as soon as the roller reaches the shoulder 71, the weight 72 will exert its energy and rock the shaft 64 and cause the lever 62 to move to the left, thereby shifting the shaft 36 and causing the finger 43 to carry with it the trolley on to the track section 16. It will be noted by reference to Fig. 3, that the cam 34 is of such width that before the finger 40 passed from off the cam, that the finger 43 passes on to the same, so that there will be no danger of the cam interfering with the proper operation of the shaft. The shaft will remain in its shifted position until the roller passes around the lower end of the spring and against its inner face, whereupon, on the upward movement of the dipping elevator, the shaft will be shifted back to its normal position.

105 In order to shift the trolley that has just been dipped from the track section 16 onto the section 19, there is a finger 74 provided which is rigid with a collar 75, keyed to the shaft 36. When the shaft 36 is shifted in the manner above described, to transfer a loaded trolley on to the section 16, the finger 74 contacts with the hanger of the trolley just elevated and shifts it on to the section 19, thereby leaving the section 16 clear to receive the freshly loaded trolley. As above stated, there is means provided for holding a trolley in the proper position upon the dipping elevator, while the same is ascending and descending. This means comprises a lever 76 that is fulcrumed upon a bracket 77, rigid with the bend 21 of the beam 5, and carries two fingers 78 and 79 (Fig. 3,) that are adapted to straddle the hanger, as shown, and thus secure the object sought. These fingers are moved into and out of position relatively to the hanger by a lever 80, one end of which is pivoted to the lever 76, and the other end pivoted to one end of a lever 81 fulcrumed at 82 on the beam 5, the 115 120 125 130

other end of the lever 81 being provided with a crotch 83 that straddles a pin or stud 84 carried by the lever 46. From this arrangement, it will be seen that when the lever 46 is actuated in the manner described, it will draw the upper end of the lever 81 to the right and push its lower end to the left, thereby exerting a thrust upon the lever 80, which will be transmitted to the lever 76 and cause its lower end to move to the right, thereby projecting the pins into operative engagement relatively to the hanger of the trolley that is upon the section 16.

The discharge elevator, to which reference has been made, comprises the head 15, which as shown in Figs. 3 and 4, is provided with two lateral extensions 85 that work in the guideways 14, the lower end of the head being provided with a yoke 86 that straddles the track section 16, as clearly shown in Figs. 3 and 4. To the lower end of the yoke arms are rigidly connected two bars 87, the outer ends of which are secured by bolts 88 to the section 19, said bolts forming fulcrums or pivots upon which the said section may turn through a limited arc. Connected with the bars 87 and held assembled at one end thereof by the bolts 88, are two brace bars 89, the upper ends of which are bolted at 90, on opposite sides of the head 15, these bars 89 serving to support the outer end of the track section 19.

Vertical motion is imparted to the head 15 by means of a cam 91 carried by one end of a lever 92 fulcrumed at 93 on one of the fixed beams 11, the outer end of the lever having pivotally connected with it, one end of a link 93^a, the other end of which is fulcrumed at 94 upon the beam 5. Secured to the head 15 is a roller 95 that is adapted to bear upon the cam 91, as clearly shown in Figs. 1 and 2. It will be seen from this arrangement that when the skeleton frame begins to descend, the cam will be thrown upward by reason of the draft exerted upon the lever 92, by the link 93^a, thereby causing the head 15 to be lifted, and with it the track section 19, which will be raised until it alines with the off-take track 22, whereupon the trolley carried by the section 19 will be discharged upon the return movement of the skeleton frame, and the head will again resume its normal position.

In order to prevent a trolley from running off the section 19, there is a stop device which comprises a lever 96 pivotally connected with one of the bars 89. One end of the lever is provided with a toe 97 that extends down into the track section 19 and in the path of the trolley, thus to hold it from running off the track section, the other end of the lever being borne up by a spring 98 carried by a stud or post 99 secured to said track section. Said track section also carries a standard 100, having a hooked end

which is designed to engage with a hooked catch 101 carried by one of the bars 89. It will be seen from this arrangement that when the section 19 is elevated, and its beveled end contacts with the end of the off-take track 22, the rear end of the section 19 will be tilted, thereby moving its forward end downward relative to the lever 96 and causing the toe 97 of the latter to be moved out of the path of the trolley, which will then be discharged upon the off-take track, and upon the track 19 resuming its normal position, the hooked members 100 and 101 will engage with each other and thereby prevent the track 19 from dropping too far, the spring 98 which is compressed during tilting of the section 19 serves to cushion the descent of the section, and to cause it to resume its proper alignment.

The means for raising and lowering the dipping elevator comprises, in part, a cam wheel 102 that is mounted upon a shaft 103 supported by a suitable framework 104. This shaft also carries a gear wheel 105 that meshes with a pinion 106 carried by a shaft 90 bearing and gear wheel 107, which latter meshes with a pinion 108, mounted upon a shaft 109, carrying a pulley 110, that is driven from any suitable source of power through the medium of a belt 111. As shown in Fig. 9, the rim 102 of the cam wheel is T-shaped, and is engaged on its inner face by rollers 113, carried by a casting 115, that is mounted upon a beam 116 that is mounted upon a bracket 114 on the frame 104, the casting 115 having combined with it a roller or wheel 117, to bear against the periphery of the cam, and thus hold the rollers 113 in operative relation thereto. Pivoted to the casting 115 is one end of a rock arm 118, the other end of which carries a cam head 119, the head being supported by a shaft 120, that works in a slotted bearing 121, bolted to the base of the frame 104. The cam head is provided with an off-set 122 through which projects a bolt 123, having at one end an eye 124 to which is attached the hoisting or operating rope 125, the object of the rocking lever being to keep the rope under requisite tension and also to permit its rapid feeding out upon the descent of the dipping elevator.

The outer end of the lever carries a shackle 126 between the arms of which is mounted a grooved sheave 127. The hoisting rope 125 passes around the cam head 119 up along the under side of the lever 116, then down and around a sheave 128 secured to the floor, thence up and around two overhead sheaves 129, secured above the apparatus, and its free end is secured in an eye 130, carried by a bracket 131, bolted to the beam 4. It will be seen that when the dipping elevator is in its raised position that the roller 117 will bear upon the bellied portion of the cam, and

then as the cam revolves and approaches the flatter portion of the cam, that the beam or lever 116 will be depressed, thereby paying out the rope 125 and permitting the dipping 5 elevator to approach the dipping tank 132.

It will be seen from the foregoing description that by arranging the mechanism as herein described, that the proper feeding, dipping, and discharging of the articles will 10 be accomplished in a thoroughly practical manner, and with rapidity, and further, that the necessity of numerous attendants to secure the proper operation of the machine is rendered entirely unnecessary.

Having thus described my invention, what I claim as new, and desire to secure by Letters-Patent, is,—

1. In a dipping machine, in combination with a frame of an ontake track sustained 20 thereby and an offtake track, a dipping elevator to receive the work from the ontake track, a discharge elevator to receive the dipped work from the dipping elevator and convey the same to the offtake track, each 25 of said elevators having a track section, a work-supporting trolley to pass from the ontake track to the offtake track section of the dipping elevator, from said track section of said elevator to that of the discharge elevator, and from the track section of the discharge elevator to the offtake track, means 30 to operate said elevators, and means to control the passage of the work-supporting trolley with respect to the said tracks and elevators.

2. In a dipping machine, the combination of a frame an inclined ontake track sustained thereby, a work-engaging trolley to operate on the same by gravity, an inclined offtake 40 track mounted in the frame, a dipping elevator to receive the said trolley from said ontake track, a discharge elevator having a tilting track, means to operate said elevators, means actuated by the movement of the dipping elevator to cause the said trolley to

pass from the ontake track to the dipping elevator, and subsequently from the latter to the tilting track of the discharge elevator, means to tilt the track of the said discharge elevator when said track alines with the offtake track and cause said trolley to pass by gravity from said tilting track to said offtake track and means for controlling the passage of the trolley between the said tracks and elevators.

3. In a dipping machine, the combination of a frame a dipping elevator mounted therein, a discharge elevator, means to operate said dipping elevator, and a cam lever, operated by the dipping elevator to operate 60 said discharge elevator.

4. In a dipping machine, the combination of a frame an inclined ontake track sustained therein, a work-carrying trolley to operate on the same by gravity, an inclined offtake 65 track, a dipping elevator to receive the said trolley from said ontake track, a discharge elevator having a tilting track, means to operate said elevators, means actuated by the movement of the dipping elevator to cause 70 the said trolley to pass from the ontake track to the dipping elevator and subsequently from the latter to the tilting track of the discharge elevator, means to tilt the track of the said discharge elevator when said track 75 alines with the offtake track and cause said trolley to pass by gravity from said tilting track to said offtake track, and means coacting with said tilting track to retain the trolley on the latter until said tilting track alines 80 with the offtake track and to release said trolley when said tilting track is tilted, for the purpose set forth.

In testimony whereof I have hereunto set my hand in presence of two subscribing witnesses.

WILLIAM M. TULLEY.
